UNITED STATES PATENT OFFICE.

JOSEPH W. MOORE, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

METHOD OF MANUFACTURING SEGMENTS OF TURBINE-BLADES.

1,187,446.

Specification of Letters Patent. Patented June 13, 1916.

Original application filed August 11, 1913, Serial No. 784,633. Divided and this application filed February 24, 1914. Serial No. 821,316.

To all whom it may concern:

Be it known that I, JOSEPH W. MOORE, a citizen of the United States, residing at West Allis, Milwaukee, in the county of Milwaukee and State of Wisconsin, have invented 5 a certain new and useful Improvement in Methods of Manufacturing Segments of Turbine-Blades, of which the following is a specification.

10 This invention relates to a method of manufacturing segments of turbine blades.

This invention primarily concerns segments of turbine blades in which a base is cast around the ends of the blades. Heretofore it has been difficult to satisfactorily cast 15 said base with the blades in correct position. Moreover it has been difficult to secure a perfect surface of the cast metal between the blades, as this surface is unmachinable 20 because of inaccessibility after casting.

The object of this invention is to provide 25 a method which will insure accuracy of spacing and angling of the blades as well as correct radial position, and accuracy of the unmachinable wall of the space between 30 blades and generally facility of production of correct segments.

This case is a division of application Serial No. 784,633, filed August 11, 1913, in 35 which case one form of apparatus adapted to carry out the present process is disclosed.

Referring to the drawing, Figure 1 shows 40 a plan view of a frame having clamped thereto a plurality of blades having a shroud strip connected thereto. Fig 2 is a sectional view of the showing in Fig. 1 on the line II-II thereof, the section through the notched blade positioning strip being taken 45 between successive notches. Fig. 3 is a developed end view of the same. Fig. 4 is a sectional side view of the same showing in addition strips temporarily clamped on opposite sides of the plurality of blades. Fig. 5 is a plan view of the showing of Fig. 4, 50 additionally showing a tamping tool in operative relation. Fig. 6 is an end view of the tamping tool. Fig. 7 is a transverse sectional detail view of the segment with the blades lying in position within the mold 55 shown in section. Fig. 8 is a transverse sectional detail view of the segment with the blades calked into position in the turbine spindle or casing.

Referring to the drawings, a segment shaped frame 1 having an arc-shaped stop 55 portion 2 at one end, has connected thereto permanently or otherwise, a notched strip 3, also arc-shaped and in parallel relation with the stop portion 2. The notches of the strip 3 are so formed that their side walls hug the 60 blade faces at the edge portions thereof as shown in Fig. 3, and tend to hold the blades in their proper angular positions and in effect interlock same to the support. Side blocks 4, 5, are positioned at the respective 65 sides of the frame 1 and with reference to the notches of strip 3, see Fig. 3, so as to insure correct angling and radial positioning of the blades 15, and are of thickness substantially equal to the width of the seg- 70 ment of blades. An arc-shaped clamping strip 6 extends from block 4 to block 5 across the segment of blades, and lies par- 75 allel to the stop portion 2. Stud bolts 7, 7, extend through the clamping strip 6 and side blocks 4, 5, into the frame 1 and serve to hold the segment of blades in place on the frame. Other stud bolts 8, 8, pass through blocks 4, 5, and into frame 1, serv- 80 ing to additionally secure these blocks in place. A strip of asbestos paper 9 may ex- 85 tend underneath clamping strip 6 and be- 90 tween it and the blocks 4, 5, and segment of blades, see Figs. 2, 3 and 4. Strips 11, 12, may be temporarily clamped at opposite 95 sides of the segment of blades by means of clamps 13, 14.

In using the method or process of this invention a plurality of blades 15 are connect- 100 ed to a shroud strip 10 by forming integral tenons of irregular section at the ends of the blades and passing same into correspondingly shaped holes punched into the shroud strip. This will insure proper angling of the blades in the strip. A temporary fas- 105 tening connection of any kind may be used. The segment of blades thus temporarily as- sembled is placed in position on the frame 1 with the shroud strip against the stop por- 110 tion 2 and the blades in their respective notches of strip 3. The end blade is brought into correct angular and radial position with its concave working face in coaction with the adjacent surface of the block 5 by simul- 115 taneously swinging, if necessary, the blades in their retaining notches as centers, thus

skewing the entire segment into correct position. After being sure that the shroud strip 10 is against the stop portion 2 at all points and the end blade against its side block 5, the clamping strip 6 with its underlying asbestos paper 9 is brought down upon the segment blades and clamped to the frame and against the side blocks 4, 5. The paper prevents injury to the blade edges. With the blades 15 thus clamped, the end blade 15 adjacent the block 5 has its concave working face in contact with the adjacent convex surface of the block 5, and the end of the blade 15 adjacent the block 4 has its convex working face in contact with the adjacent concave surface of the block 4, see Figs. 1 and 3. After ramming sand between the blades, the strips 11, 12, are temporarily clamped on opposite sides respectively of the segment of blades with their edges adjacent the ends of the blades in line and in a position a short distance nearer the adjacent ends of the blades than would correspond to the limit of entry of cast metal between the blades, see Fig. 4, and the sand is then brushed out or otherwise removed from between the ends of the blades up to the edges of the strips 11, 12. These strips 11, 12, are then moved away from the ends of the blades the same short distance referred to, see Fig. 5, and a tamping tool 16, having a cross section substantially equal to the cross section of the space between two blades, is rammed between each two of the blades until a shoulder 17 formed thereon is brought into contact with the ends of the blades. This will gage and positively determine the limit of entry of the cast metal between the blades during the casting operation. The strips 11, 12, are now removed.

A mold of sand having previously been prepared by embedding a pattern therein of the proper shape to accommodate the substitution of the frame as prepared with its segment of blades and also to additionally form a space 18 in the mold adapted to receive the cast metal about the ends of the blades of the segment, the frame with the segment of blades is placed therein with the free ends of the blades projecting into the space 18, see Fig. 7. The mold after insertion of the frame and blade segments is then properly closed by the cope, proper and necessary sprue and riser openings having been formed leading to and from the space 18 for the cast metal. The ends of the blades, it should be stated, may be notched or roughened or formed in any way to make a positive lock with the cast metal, see Figs. 2, 4, 7 and 8. The metal is then cast about

the ends of the blades and as soon as the metal has set the frame is removed from the mold and the clamping strip 6 is loosened from the frame or entirely removed, to permit of the shrinkage which takes place during cooling. The segment is then machined by turning down the cast metal to proper shape for calking in the spindle or cylinder of the turbine. The fastening to the spindle is preferably made by undercutting the parts rather than by dove-tailing; as this affords a positive locking of the parts.

It should be understood that it is not desired to be limited to the exact details of construction of apparatus shown and described, or details of process disclosed, for obvious modifications will occur to a person skilled in the art.

It is claimed and desired to secure by Letters Patent,—

1. The process of manufacturing a turbine segment of blades which consists in clamping a plurality of blades in spaced and angled relation to a support, casting metal around the free ends of said blades, and loosening said support from said blades after said cast metal has set and before completion of contraction due to cooling.

2. The process of manufacturing a turbine segment of blades which consists in connecting spacing means to a plurality of blades, clamping said blades in spaced and angled relation to a support, casting metal around the free ends of said blades, and loosening said support from said blades after said cast metal has set and before completion of contraction due to cooling.

3. The process of manufacturing a turbine segment of blades which consists in clamping a plurality of blades in spaced and angled relation to a support, casting metal around the free ends of said blades, and loosening said support from said blades as soon as said cast metal has set.

4. The process of manufacturing a turbine segment of blades which consists in connecting spacing means to a plurality of blades, clamping said blades in spaced and angled relation to a support, casting metal around the free ends of said blades, and loosening said support from said blades as soon as said cast metal has set.

In testimony whereof, the signature of the inventor is affixed hereto in the presence of two witnesses.

JOSEPH W. MOORE.
